UNITED STATES PATENT OFFICE.

JAMES SCOTT McCORMICK, OF WEST MILLGROVE, OHIO; SARAH YATES ADMINISTRATRIX OF SAID McCORMICK, DECEASED.

REVOLVING SAFE.

941,940.

Specification of Letters Patent. Patented Nov. 30, 1909.

Application filed October 7, 1908. Serial No. 456,589.

To all whom it may concern:

Be it known that I, JAMES S. McCORMICK, a citizen of the United States, residing at West Millgrove, in the county of Wood and State of Ohio, have invented a new and useful Revolving Safe, of which the following is a specification.

My invention is an improvement in revolving safes, the object of the invention being 10 to provide a fire and burglar proof safe in which the door will be protected by outer casings when the safe is closed.

The invention consists of a revolving cylindrical safe, adapted to rotate within a 15 cylindrical casing and having a cylindrical shield around the casing, the shield revolving with the safe.

The details of my invention are set forth hereafter, particularly pointed out in the 20 claims, and illustrated in the accompanying drawings, in which,

Figure 1 is a perspective rear view of my complete safe closed. Fig. 2 is a perspective front view showing the safe open. Fig. 3 25 is a horizontal section taken through the safe as shown in Fig. 1, about midway its height. Fig. 4 is a similar sectional view the safe being open, as shown in Fig. 2. Fig. 5 is a vertical section taken centrally through the 30 safe, the door being shown in elevation. Fig. 6 is a detail perspective view of the top plate. Fig. 7 is a detail, detached, perspective view of the casing. Fig. 8 is a perspective view of the shield. Fig. 9 is a 35 perspective view of the safe proper removed from the casing.

In the construction of my improved safe I employ a cylindrical casing A, having the integral base A', and upwardly open. This 40 casing is cut out on one side at A², and circumferentially slotted on the opposite side at A³. A stub shaft A⁴ reduced and threaded at its upper end projects centrally from the base within the casing. A top plate B 45 of greater diameter than the casing is adapted to fit over and close the casing.

A stub shaft B' depends centrally from this top plate and is reduced and threaded at its lower end.

50 The safe proper consists of a cylindrical casing C having integral top and bottom pieces C', projecting slightly beyond the side walls of the safe. The safe is cut out on one side, and in this cut out portion is hinged 55 the door C², the door and edges of the cut out

portion having the usual beveled edges and adapted to be locked by any desired form of combination lock as shown at C³, the locking bolts being shown at C⁴. The ends C' are centrally perforated and into these 60 perforations extend the stub shafts A⁴ and B', respectively. Nuts D fit on the threaded ends of the shafts, said nuts being inside the safe C and just above the shaft A⁴, is a false horizontal bottom C⁵.

After both nuts have been placed in position the safe is securely but revolubly held within the casing A. In order that the safe may revolve easily on the stub shafts an annular groove A⁶ is formed on the inner face 70 of the base A', in which are placed anti-friction balls A⁶, on which the bottom of the safe rests.

On the upper face of the base plate is formed an annular groove E, exterior of the 75 casing A, and a similar groove E', of the same size is formed in the under face of the top plate B. A cylindrical shield E² fits loosely over the casing A, resting in the groove E, and the upper edge of the shield 80 extends upwardly into the groove E'. The shield is cut out on one side as at E³. A suitable combination lock F, is secured in one side of the safe and an operating rod F', extends from said lock through the slot 85 A³ and the shield E² carrying at its inner end the mechanism for operating the combination and at its outer end the handle F². These parts will be more fully described 90 hereafter.

In assembling these various parts the safe is placed within the casing and the shield is placed in position around the casing, and the top placed on last. After all these parts are assembled the nuts D are placed in position and all parts are firmly held together. The false bottom C⁵ is supported above the real bottom by a depending flange C⁶ and may be lifted vertically in order that the nut may be placed on the shaft A⁴.

100 Any form of lock which will lock the safe C to the casing A can be employed. In Figs. 3 and 4 I have shown such a lock in outline. This lock carries a bolt F⁴ which engages a socket F⁵ formed in the inner face of the 105 casing A adjacent what may be termed the inner end of the slot A³ which is an end at which the handle F² of the lock F rests when the safe is in closed position as shown in Fig. 3. By turning the operating handle so 110

as to withdraw the bolt F^4 from the socket F^5 the safe may be rotated, as may also the shield E^2 .

It will be obvious from the drawings that 5 when the operating handle is at the locking end of the slot A^3 the door C^2 of the safe will be out of alinement with the opening A^2 in the casing A . But by operating the lock F and releasing the safe from locking engagement with the stationary casing A the handle F^2 can be moved along the slot A^3 of the casing A thereby bringing the opening E^3 and the safe door C^2 into alinement with the opening A^2 .

15 Having thus fully described my invention what I claim as new and desire to secure by Letters Patent is:—

1. The combination with a revolute safe, of a stationary casing inclosing same, a revolute shield surrounding the casing and means connecting the shield and safe.

2. The combination with a cylindrical stationary casing of a cylindrical safe rotatably mounted within the casing, the casing having a cut out portion through which the door of the safe can swing, and operating means connected to the safe and extending through

the stationary casing permitting rotation of the safe to bring the safe door into and out of alinement with the opening in the casing. 30

3. The combination with a cylindrical, stationary casing cut out on one side and circumferentially slotted on the opposite side, a shield revolute with respect to the casing, of a safe revolutely mounted in said casing, 35 and a rod working in said slot and connecting the shield and casing.

4. The combination with a cylindrical stationary casing, having an outwardly projecting, grooved base, said casing being cut 40 out on one side and slotted on the opposite side, of a cylindrical safe revolutely mounted within the casing, a top plate having an annular groove on its under surface, a cylindrical shield adapted to rotate in the grooves 45 of the base and the top plate, said shield being cut out on one side, and a rod secured at one end to the safe and extending through the slot of the casing and through the wall of the shield.

JAMES SCOTT McCORMICK.
